UNITED STATES PATENT OFFICE

102,250

DESIGN FOR A PLASTIC SHEET OR SIMILAR ARTICLE

William Bowker, Union, N. J., assignor to Celluloid Corporation, a corporation of New Jersey

Application November 23, 1935, Serial No. 59,719

Term of patent 7 years

To all whom it may concern:

Be it known that I, William Bowker, a citizen of the United States, residing at Union, county of Union, State of New Jersey, have invented a new, original, and ornamental Design for a Plastic Sheet or Similar Article, of which the following is a specification, reference being had to the accompanying drawing, forming part thereof.

In the accompanying drawing:

The figure is a plan view of a plastic sheet or similar article showing my new design.

The thickness of the sheet or similar article is not an important part of the design. The characteristic feature of my design consists of the

ornamentation appearing on the sheet or similar article. In the drawing the light vertical lines 1 indicate light colored and/or translucent portions. The heavy diagonal portions 2 indicate dark colored strata and the light diagonal portions 3 indicate strata presenting pearl luster effects and which have a color that contrasts with and/or is lighter than the color of the portions 2.

I claim:

The ornamental design for a plastic sheet or similar article, substantially as shown and described.

WILLIAM BOWKER.
